REVERSIBLE SCREW FEEDER AND CRUSHER
MECHANISM WITH MEANS TO AUTOMATI-
CALLY EJECT INDESTRUCTIBLE OVER-
SIZE FOREIGN MATTER

Robert N. Dulaney, Chattanooga, Tenn.; Elizabeth M. Dulaney, executrix of said Robert N. Dulaney, deceased, assignor of one-half to Ralph Burch, Washington, D. C.

Application May 24, 1944; Serial No. 537,130

12 Claims. (Cl. 241—35)

1

The invention relates to a material feeding mechanism, and more especially to a feeder and ejector mechanism for a screw-feed type of conveyor, such for example as a coal stoker, directing soft, semi-lump or other fuel material to a furnace, or the like; for the burning thereof.

The primary object of the invention is the provision of mechanism of this character, wherein stoppage or damage thereto by foreign objects will be prevented, during the operation thereof in conveying coal or other material thereby, the mechanism being novel in its construction, and unique in the working of the same, as the presence of any foreign matter in the material will be ejected from the mass, without damage to the said mechanism or the stoppage in the operation of the same when conveying material thereby.

Another object of the invention is the provision of mechanism of this character, wherein the full power of its driver will be utilized to crush foreign matter present in the material when conveyed thereby, without endangering the power unit or driver, while indestructible foreign matter contained in the material will be automatically ejected from the mechanism, and thereby relieving the driver and adjuncts thereto from disablement therefrom, and with resultant continuity of operation of the mechanism.

A further object of the invention is the provision of mechanism of this character, wherein the ejected matter can be readily and easily removed, and such mechanism does not require constant attendance, as the ejected matter need not be removed immediately, for the continued operation of the mechanism. Other devices, such as shear pins, throw-out means, etc., are presently used to protect such conveyor mechanism, but these require that the impeding object be removed before the operation of the conveyor can be resumed, and often, as in the case of stokers, there is no one in constant attendance, so that inconvenience and sometimes damage results.

A still further object of the invention is the provision of mechanism of this character, which is simple in construction, thoroughly reliable and efficient in operation, strong, durable, entirely automatic in the working thereof, requiring little or no attention, the parts being readily accessible for repairs or inspection, and inexpensive to manufacture and install.

With these and other objects in view the invention consists in the features of construction, combination and arrangement of parts as will be hereinafter more fully described, illustrated in the accompanying drawings, which disclose the

2

preferred embodiment of the invention, and pointed out in the claims hereunto appended.

In the accompanying drawings:

5 Figure 1 is a fragmentary vertical longitudinal sectional view through a coal stoker showing the mechanism constructed in accordance with the invention installed therewith.

10 Figure 2 is a sectional view taken on the line 2—2 of Figure 1 looking in the direction of the arrows.

15 Figure 3 is a fragmentary side view feed screw and the crusher head in associated relation to each other, of the mechanism, these being on an enlarged scale.

20 Figure 4 is a diagrammatic view of a developed profile of part of the face along the periphery of the crusher head and helically shaped screw rib of the feed screw of the mechanism.

25 Figure 5 is a detail side view of the ratchet drive means of the mechanism.

Figure 6 is a view similar to Figure 5 showing the drive means in reverse.

Figure 7 is a plan view thereof.

Figure 8 is a side view of the spreader jaws in spread relation to each other of the drive means.

25 Figure 9 is a diagrammatic view of the feed control device for the mechanism.

Figure 10 is a detail elevation of the reverse stop device of the mechanism.

30 Figure 11 is a detail elevation of the calibrating device for the spreader jaws of the mechanism.

Similar reference characters indicate corresponding parts throughout the several views in the drawings.

35 Referring to the drawings in detail A designates generally a portion of a coal stoker, and B denotes generally the screw-feed mechanism, respectively, the latter constituting the present invention, and hereinafter fully described.

40 The stoker A in this instance is shown merely to illustrate the application and manner of use of the mechanism B, as the latter is susceptible of use on other conveyor machines or apparatuses,

45 and comprises a hopper shaped body 10 for containing soft coal or other like fuel for stoking a furnace or other like structure. At the lower smaller delivery mouth 11 of the body 10 is a horizontally arranged cylindrical or tubular shaped neck 12, which at one end portion 13 extends be-

50 yond the body 10 into abutting relation to a stand casting 14, the latter having a coupling sleeve formation 15, centrally aligned with the longitudinal axis of the neck 12, and in conformity with this alignment is a feed screw conduit 16 which

delivers material from the body 10 to the furnace or the like not shown.

Coextensive with the neck 12 and the conduit 16 and working within the same is a rotatable feed screw or worm rib shaft 17, it working through a clearance therefor in the crusher head 18 removably fitted snugly within the sleeve formation 15 of the stand casting 14. The crusher head 18 at its face confronting the neck 12 is divided into a number of crushing teeth or projections 19, each of which is helically shaped, so as to approximate extensions of the screw rib 20 of the screw or shaft 17, so that any object entering the clearance 21 in the head 18 for the said screw or shaft 17, but partly outside of such clearance, will be subjected to direct right-angle shear between the screw rib 20 and one of the teeth or projections 19 for crushing action on the object. This construction prevents any wedging action, and leaves the worm, if stalled by a bolt or other hard object, free to turn backward. This overcomes a common occurrence, that is, objects being tightly wedged between the worm-rib and the entrance to the conduit 16, so that it is difficult to turn the worm or screw backward, and impossible to turn it forward.

The stand casting 14 next to the head 18 has created therein below the neck 12 a pit 22 for receiving uncrushed objects from the neck, the communication between these being had by a drop door 23 which is vertically swingable on a hinge 24 and supported in closed position by a lip 25. The hinge 24 is supported in slotted ways 26 so that the door 23 can slide back to clear the lip 25 and fall open, as best seen by dotted lines in Figure 1 of the drawings. A ratchet shaped lug 27 made from any suitable springy material, is secured to the door 23 at its uppermost side, and is shaped to be depressed by large pieces of coal, etc., which may be dragged over it by the worm rib or screw shaft 17. However, if the worm rib or screw 17 turns backward, the coal in the space between the lug 27 and the head 18 will force the lug 27 together with the door 23 back, and when the door clears the lip 25 the said door will fall open. A door or removable panel 28 is provided in the side of the casting 14 for access to the pit 22 so that material may be removed therefrom, and the door 23 reset closed.

At the end of the neck 12 remote from the end portion 13 is a stand casting 29 forming a housing 30 in which is horizontally journaled in any suitable manner a driving shaft 31 having a coupling 32 connected with the screw or shaft 17 designed to resist thrust, or longitudinal movement of the worm in either direction.

In association with the shaft 31 is a ratchet drive mechanism for the shaft 17, and comprises a toothed wheel 33 keyed or otherwise secured to the shaft 31. A connecting rod 34 is pivoted to a crank 36, which latter is adapted to transmit a reciprocating motion to the ratchet drive mechanism and such crank is formed with an elbow arm 37 carrying the latter back and forth in an arc about the shaft 31. The said mechanism further involves a block 38 which is pivotally mounted on a pin 39 connecting the rod 34 with the arm 37. Within the block 38 are ratchet plungers 40 and 41, respectively, these being workable in suitable slots in the said block 38, and are urged outward by springs 42. The plunger 40 is the forward ratchet and the plunger 41 is the reverse ratchet, in the operation of the ratchet mechanism.

On the block 38 are closely arranged stud journals 43 carrying rollers 44 which fit into notch like seats 45 closely spaced apart from each other and formed in the inner edges of opposed jaws 46, pivoted at 47 to the arm 37, as best seen in Figure 3 of the drawings. These jaws 46 are forced together by a spring 48 carried on an adjustable coupling pin 49 loosely fitted in the ends of the jaws 46 remote from the pivoted ends thereof. 10 The jaws 46 are spread apart by the rollers 44 passing from one pair of seats 45 to the other pair thereof, as will be apparent from Figures 6 and 7 of the drawings.

Cooperating with the ratchet mechanism is a feed control device, comprising a segmental-shaped shield wing 50 formed at the periphery of a mutilated gear 51 freely or loosely mounted on the shaft 31, and this gear meshes with a gear 52 fixed to an axle 53 which is extended outside of the housing 30, while at the outer end of this axle is a pointer hand 54 having a latching pin 55, which is spring controlled, to engage in holes 56 in a dial area having identification markings 57, and in this manner the hand is held in any selected or desired adjusted position, as will be best seen in Figure 9 of the drawings.

On the plunger 40 is a striker lug 58 which extends over the shield wing 50 and prevents this plunger from engaging in any of the teeth in the wheel 33 as covered by the said shield wing 50. By changing the position of the shield wing 50 it will be seen that the amount of material fed by one revolution of the power crank 58 can be varied, or entirely cut off. The setting of the shield wing 50 is indicated by the numeral identification markings 57 on the dial area toward which the pointer hand 54 points. It will be noted that there is no lug on the reverse plunger 41, so that the shield wing 50 does not affect the reverse motion or movement.

On the shaft 31 is a reverse stop device, which includes a collar 59 secured to the said shaft and carrying a pin 60, while next to the collar 59 and freely movable on the shaft is a ratchet wheel 61, which is free to turn in the normal forward direction of the worm 20 of the screw 17, but is prevented from turning in the opposite direction by a ratchet dog or pawl 62 which acts as a ratchet in association with the said wheel. The wheel 61 is provided with a radial pin 63, which engages the pin 60. The collar 59 can revolve freely in the direction shown by the arrow in Figure 10 of the drawings, pushing the pin 63 and with it the wheel 61; but in reverse, the pin 55 60 leaves the pin 63 and makes approximately a full revolution before engaging it on the other side, as shown by dotted lines, in said Figure 10, when the mechanism will be stalled by the ratchet dog or pawl 62 acting through the wheel 61 and the pin 63.

In the normal operation, the crank 58 revolved by a power unit, not shown, imparts, through connecting rod 34, a reciprocating motion to the crank 36 carrying the block 38, which latter in the extreme positions are shown in Figure 9 of the drawings. The ratchet plunger 41 will move to the left, sliding over the teeth of the wheel 33 without turning it, but on the swing to the right it will engage the first tooth not covered by the 70 shield wing 50 and revolve the wheel 33 and through it the worm 20, in an arc equal to 2, 4 or 6 spaces depending on the setting of the shield wing 50. This cycle is repeated over and over, and this constitutes the normal action of the mechanism.

75 If a foreign object, for example a bolt, comes

between the rib of the worm 20 and the crusher head 18 the worm will be stopped. Then the connecting rod 34 pulling on the pin 39 will force the block 38 to revolve about the said pin 39, moving such block over into reverse position as shown in Figure 6 of the drawings. This change in position is resisted by the pins 44 with the rollers 43 thereon, having to spread the jaws 46 to pass from one position to the other as shown in Figure 8 of the drawings. The amount of resistance is accurately adjusted as hereinafter described.

When the drive is reversed, the ratchet plunger 40 drives the wheel 33 in a counter-clockwise direction, thus turning the worm backward. The pressure of coal against the lug 27 causes the door 23 to move back and fall open, spilling the part of the coal nearest the head 18 and with it the impeding object, into the chamber 22. At approximately one reverse revolution of the worm, the reverse stop device becomes active, under its construction as before set forth, changing the position of the block 38 to that as shown in Figure 5 of the drawings, and normal operation of the worm is resumed. If it should happen that a second impediment occurs before the chamber 22 is cleaned out and the door reset, it is probable that the impeding object will be worked down into the coal in the said chamber 22 by the repeated back-and-forth movement of the worm, since these objects are usually heavier than coal; but if this does not happen, no damage would result, since the mechanism would change from one position to the other until the impeding object is removed.

To calibrate the resistance in the jaws 46 so that the amount of force required to change the position of the block 38 would be near the safe limit of the motor or power unit, but would not endanger it there has been provided a calibrating device. For example, assume that it has been calculated that the block 38 should move from one position to the other when the torsion about the pin 39 is between 100 and 110 inch-pounds. This calibrating device comprises an arm 64 with a hole 65 to slip over the pin 39 and a pin 66 to engage the hole 67. On the arm 64 is a weight 68 to slide from one position shown by full lines to that position shown by dotted lines, best seen in Figure 11 of the drawings. It is designed so that the torsion about the pin 39 with the weight 68 in one position is 100 inch-pounds, and with the weight in the other position, 110 inch-pounds.

With the arm 64 in the position and the worm resisted against turning, the pressure exerted by the spring 48 to hold the jaws 46 together is adjusted by turning the nut 69 on the coupling member 49 so that the weighted arm 64 will not turn the block 38 with the weight in the first position, but will render it quicker acting into reverse if the weight is shifted to the second position, but this adjustment can be checked from time to time, after the stoker is in service, so that any change in the elasticity of the spring 48 can be compensated. The exact amount of torsion at which the change should occur can be calculated from the known factors, and it can be readily seen that the motor or power unit will be fully protected, but will use its full power to attempt to crush any impeding object before rejecting it.

What is claimed is:

1. Driving mechanism of the character described comprising a screw conveyor, driving means having a shiftable portion for rotating said screw conveyor in alternate directions, power means for reciprocating said driving means to

normally drive said conveyor in a forward direction, and automatic means for shifting said driving means to alternate driving positions when the movement of said conveyor is retarded.

- 5 2. A mechanism as described in claim 1 including means actuated by the reverse movement of said conveyor to shift said driving means to a forward drive position after limited reverse movement of the conveyor.
- 10 3. Driving mechanism of the character described comprising a screw conveyor, a ratchet drive having a shiftable portion for rotating said conveyor either forward or backward, power means for reciprocating said ratchet drive to normally drive said conveyor in a forward direction, and automatic means for shifting said ratchet drive to alternate driving positions when the movement of said conveyor is retarded.
- 15 4. Driving mechanism of the character described comprising a screw conveyor, a drive wheel for rotating said conveyor, a drive having a shiftable portion for rotating said wheel in alternate directions, power means for reciprocating said drive to normally rotate said conveyor in a forward direction, and automatic means for shifting said drive to alternate driving positions when the movement of said conveyor is retarded.
- 20 5. Driving mechanism of the character described comprising a screw conveyor, a gear wheel for driving said conveyor, a shiftable double acting driving member for rotating said gear wheel in alternate directions, power means for reciprocating said driving member to normally drive said conveyor in a forward direction, and automatic means for shifting said double acting driving member to alternate driving positions when the movement of said conveyor is retarded.
- 25 6. Driving mechanism of the character described comprising a screw conveyor, a gear wheel for driving said conveyor, double acting pawls shiftably mounted for alternate driving engagement with said gear wheel for driving the same in alternate directions, power means for reciprocating said pawls to normally drive said conveyor in a forward direction, and automatic means for shifting said pawls to alternate driving positions when the movement of said conveyor is retarded.
- 30 7. Driving mechanism of the character described in claim 6 including adjustable means for resisting the shifting movement of said pawls.
- 35 8. Driving mechanism of the character described in claim 6 including means actuated by the reverse movement of said conveyor to shift said pawls to a forward driving position after limited reverse movement of said conveyor.
- 40 9. Mechanism of the character described comprising a material conveyor, means for moving said conveyor in a forward and backward direction, a crusher head at the forward end of said conveyor, a depository beneath and communicating with said conveyor adjacent said crusher head, a movable cover normally closing said depository, and compressible means cooperating with said cover and disposed in the path of the flow of material moved by said conveyor adapted to move said cover to an open position upon reverse flow of the material.
- 45 10. Mechanism of the character described comprising a material conveyor, means for moving said conveyor in a forward and backward direction, a crusher head at the forward end of said conveyor, a depository beneath and communicating with said conveyor adjacent said crusher head, a horizontally movable cover normally closing said depository, and compressible means co-

operating with said cover adapted to project into the path of the material upon backward movement of said conveyor whereby said cover is moved to an open position to allow the material to discharge into said depository.

11. Mechanism of the character described comprising a material conveyor, means for moving said conveyor in a forward and backward direction, a crusher head at the forward end of said conveyor, a depository beneath and communicating with said conveyor adjacent said crusher head, a sliding drop door for said depository normally supported in a horizontal closed position, and means associated with said door actuated by the backward flow of material to move said door to an open position and allow the material to discharge into said depository.

12. A mechanism of the character described comprising a screw conveyor, reciprocating driving means having a shiftable portion for rotating said conveyor in alternate directions, power means for reciprocating said driving means to normally drive said conveyor in a forward direction, automatic means for shifting said driving means to alternate driving positions when movement of said conveyor is retarded, a crusher
